UNITED STATES PATENT OFFICE

EDMOND BAYLE, HENRI GEORGE AND AUGUSTIN MACHE, OF PARIS, FRANCE

PROCESS FOR THE PROTECTION AND AUTHENTIFICATION OF ARTICLES

No Drawing. Application filed January 24, 1929, Serial No. 334,849, and in France January 28, 1928.

The present invention has for its object a process for the protection and authentification of deeds, cheques, receipts, contracts, coupons, tickets, trade marks, guarantee stamps and in a general manner of all documents, printed or manuscript, or even objects.

This process consists in the systematic use, for the printings or inscriptions, of an ink, varnish or coating, containing a coloured indicator, that is, a body of which the colour is a function of its ionic state, so that, by varying this ionic state by suitable reagents, there are obtained predetermined colorations, a buffer mixture being added to the ink, varnish or coating in order to render the coloured indicator immune against the effect of atmospheric agents, so that this ink, varnish or coating will have a stable ionic state and therefore a well-defined colour, not varying under the action of slight accidental variations of acidity or alkalinity of the atmosphere. When the nature of the object does not allow any printing on its surface, for example in the case of pastes, plastic materials or like products, the present process remains applicable by the incorporation, in the mass of the said objects, of the active ionized and coloured material.

The authentication consists in developing upon the surface of the object, by means of one or more suitable reagents, one or more determined ionic states, corresponding to one or more characteristic colorations. The number of the ionic states, and consequently that of the characteristic colorations, is unlimited. The authentication can take place by any process (strokes of the pen, affixing moist stamps, etc.) allowing of applying to the surface of the document or of the object to be checked a certain quantity of the suitable reagent or reagents.

The guarantee against an imitation or falsification of documents or objects, protected by the use of ink, varnish or coating in accordance with the present invention, resides in the composition of the ink, varnish or coating, of which the ionic state for a determined coloration is comprised between two limits as close as may be desired and of which the

number of characteristic changes may be as large as is necessary.

These properties characterize the inks, varnishes or coatings forming the subject of the present invention and differentiate them from inks, varnishes or coatings of which variation of colour is obtained by chemical reactions.

The following example of an ink will assist in explaining the invention:

Chloro-zincic derivative of the bromoethylate of hexamethyl- and pentamethylmonoethyl-p-rosaniline 3 gr.

Sodium salt of o-toluidine-diazo-bi-1-naphthylamine-4-sulphonic acid 2 to 4 gr. 70

Bi-phosphate of soda 10 to 15 gr. 75

Soda 1.5 gr. 80

Glycerine 5 to 10 gr.

80

$$\text{CH}_2\text{OH}-\text{CHOH}-\text{CH}_2\text{OH}$$

Thin varnish for printing ink 100 to 500 gr. 85 (quantity sufficient to obtain the intensity of coloration desired).

The checking of an ink of this kind is effected as has been indicated above and gives with suitable reagents a determined change 90 of colour. Thus in the preceding example:

Hydrochloric acid changes the colour to green.

A mixture of glycocol, chloride of sodium 95 and hydrochloric acid changes the colour to blue-green.

A mixture of hydrochloric acid and biphenylate of potash changes the colour to blue-grey.

100

A mixture of citrate of soda and hydrochloric acid changes the colour to indigo.

A mixture of boric acid and borax changes the colour to violet.

5 The authentication reagents might likewise contain one or more of the coloured indicators or bodies having a characteristic coloration dependent on their ionic state; thus in the example given above, these reagents 10 might contain the chlorozincic derivative of the bromethylate mentioned or the sodium salt of the sulphonic acid mentioned; the mixture employed as "buffer" would remain the same.

15 The checking of the documents or objects protected by the present process is instantaneous and involves no special apparatus.

By way of example the present process is applicable to the checking of all musical and 20 artistic editions, tickets, stamps, coupons, gramophone discs, etc.

What we claim is:

1. A process for the authentication of articles consisting in incorporating to said articles 25 a product comprising a chloro-zincic derivative of bromethylate of hexamethyl- and penta-methylmonoethyl-p-rosaniline, a sodium salt of o-toluidine-diazo-bi-1-naphthylamine-4-sulphonic acid, and a mixture of a weak acid and a strong base, said product being adapted to give predetermined colorations with suitable reagents.

2. A process for the authentication of articles, consisting in incorporating to said articles 35 a product comprising a chloro-zincic derivative of the bromethylate of hexamethyl- and penta-methylmonoethyl-p-rosaniline, a sodium salt of o-toluidine-diazo-bi-1-naphthylamine-4-sulphonic acid, and a mixture of a weak acid and a strong base, said product being adapted to give predetermined colorations with suitable reagents.

3. As a new article of manufacture for the authentication of articles, a product comprising 45 a chloro-zincic derivative of bromethylate of hexamethyl- and penta-methylmonoethyl-p-rosaniline, a sodium salt of o-toluidine-diazo-bi-1-naphthylamine-4-sulphonic acid, and a mixture of a weak acid and a strong base.

4. As a new article of manufacture for the authentication of articles, a product comprising 55 a chloro-zincic derivative of the bromethylate of hexamethyl- and pentamethylmonoethyl-p-rosaniline, a sodium salt of o-toluidine-diazo-bi-1-naphthylamine-4-sulphonic acid, and a mixture of biphasphate of soda and of soda.

5. A process for the authentication of articles, consisting in incorporating to said articles 60 a product comprising a chloro-zincic derivative of bromethylate of hexamethyl- and penta-methylmonoethyl-p-rosaniline, and a mixture of a weak acid and a strong base, said product being adapted to give pre-

determined colorations with suitable reagents.

6. A process for the authentication of articles, consisting in incorporating to said articles a product comprising a chloro-zincic derivative 70 of the bromethylate of hexamethyl- and penta-methylmonoethyl-p-rosaniline, and a mixture of biphasphate of soda and of soda, said product being adapted to give predetermined colorations with suitable 75 reagents.

7. As a new article of manufacture for the authentication of articles, a product comprising 80 a chloro-zincic derivative of hexamethyl- and penta-methylmonoethyl-p-rosaniline, and a mixture of a weak acid and a strong base.

8. As a new article of manufacture for the authentication of articles, a product comprising 85 a chloro-zincic derivative of the bromethylate of hexamethyl- and penta-methylmonoethyl-p-rosaniline, and a mixture of biphasphate of soda and of soda.

9. A process for the authentication of articles, consisting in incorporating to said articles 90 a product comprising a sodium salt of o-toluidine-diazo-bi-1-naphthylamine-4-sulphonic acid, and a mixture of a weak acid and a strong base, said product being adapted to give predetermined colorations with suitable 95 reagents.

10. A process for the authentication of articles consisting in incorporating to said articles a product comprising a sodium salt of o-toluidine-diazo-bi-1-naphthylamine-4- 100 sulphonic acid, and a mixture of biphasphate of soda and of soda, said product being adapted to give predetermined colorations with suitable reagents.

11. As a new article of manufacture for 105 the authentication of articles, a product comprising a sodium salt of o-toluidine-diazo-bi-1-naphthylamine-4-sulphonic acid, and a mixture of a weak acid and a strong base.

12. As a new article of manufacture for the authentication of articles, a product comprising 110 a sodium salt of o-toluidine-diazo-bi-1-naphthylamine-4-sulphonic acid, and a mixture of biphasphate of soda and of soda.

In testimony whereof we have signed our names to this specification.

EDMOND BAYLE.

HENRI GEORGE.

AUGUSTIN MACHE.
